UNITED STATES PATENT OFFICE.

FRANK A. TRAVIS, OF KANSAS CITY, MISSOURI.

PISTON EXPANDER.

Application filed September 12, 1927. Serial No. 218,938.

My invention relates to piston expanders and one object is to provide a simple and efficient device of this character whereby engine pistons which have become worn can be expanded to their original diameters at very little cost.

A further object is to provide a device of this character with a wide range of adjustment so that it can be employed to advantage in expanding pistons of different diameters.

In order that the invention may be fully understood, reference will now be had to the accompanying drawings, in which:

Fig. 1 is a broken elevation partly in section of the device.

Fig. 2 is a detail of the piston clamping and expanding mechanism.

Fig. 3 is an inverted plan view of the parts disclosed by Fig. 2, with the wedge member of the expanding mechanism removed.

Fig. 4 shows a pair of blocks forming a part of the expanding mechanism.

Fig. 5 is a fragmentary side elevation of a portion of the frame.

In carrying out the invention I employ a frame consisting of a base 2 and a yoke 4. The base 2 is provided with diametrically opposed ears 6, between which the lower ends of the yoke 4 are held by pins 8 which may be withdrawn to permit removal of said yoke when it is desired to place the expanding mechanism, hereinafter described, within a piston.

10 designates a piston clamping member which is preferably of conical formation for engaging the open ends of pistons to be expanded. The conical member 10 is supported by an axially disposed neck 12 having a superimposed head 14 adapted to be engaged and rotated by a suitable wrench. A central bore 16 extends through the conical member 10, the neck 12 and the head 14 and is threaded at its upper portion upon a tubular member 18 provided at its upper end with a peripheral flange 20 which is journaled in a bearing 22 secured to the upper portion of the yoke 4. A peripheral shoulder 24 is formed on the upper portion of the tubular member 18 so that it may be grasped by hand or held with a wrench while the conical member is being screwed up or down.

55 The expanding mechanism for expanding the pistons includes a pair of blocks 26 and

a wedge member 28. The wedge member 28 is slidably mounted in upwardly tapered grooves 30 formed within the adjacent sides of the blocks 26, which latter are yieldably held together by suitable means such as coil springs 32. The wedge member 28 is prevented from moving laterally in any direction by flanges 34 and 36 forming sides of the grooves 30. The blocks 26 are provided at their upper portions with dovetail grooves 34^a for the reception of a complementary tongue 36^a extending across the bottom of the conical member 10 for the purpose of supporting the blocks 26.

The narrow faces 38 of the blocks 26 are curved as shown by Figs. 3 and 4, to avoid presenting sharp corners to the interior of the pistons to be expanded.

The wedge member 28 of the expanding mechanism is raised and lowered by means of a stem 40, the lower portion of which is threaded into a bore 42 extending centrally of the wedge member 28. The stem 40 extends axially through the tubular member 18 and is journaled at its upper portion in the upper central portion of the yoke 4, where it is held from longitudinal movement by a collar 42 bearing against the under surface and a peripheral shoulder 44 bearing against the upper surface of the upper transverse portion of the yoke 4. The upper enlarged end of the stem 40 is provided with a handle 46 whereby said stem may be rotated to raise or lower the wedge member 28.

In order that the pistons may be accurately expanded to a predetermined diameter, I provide gage means consisting of thumb screws 48 threaded in the opposite sides of the yoke 4.

In practice when a piston such as A is to be expanded diametrically, it is placed in an inverted position upon the base 2. The yoke 4 which was previously removed from the base 2 to allow the expanding mechanism to be inserted within the piston is then replaced, after which the piston is clamped firmly in position upon said base by proper adjustment of the conical member 10 and the tubular member 18. The handle 46 is then rotated in the proper direction to raise the wedge member 28 which forces the blocks 26 outwardly far enough to engage the inner surface of the cylindrical wall of the piston A and expand said wall diametrically until checked by the gages 48 which were previously spaced apart the proper distance.

After the piston has been expanded as stated, the conical member 10 is adjusted upwardly out of engagement with said piston to relieve the pressure thereon, after which the 5 pins 8 are withdrawn to permit removal of the yoke 4 and the expanding mechanism.

Expansion of the piston is facilitated when the same is in a highly heated condition. Owing to the wide range of movement of the 10 expanding mechanism, it will be understood that pistons of different sizes can be expanded without changing blocks 26 and the wedge 28 for larger or smaller sizes.

While I have shown the preferred form 15 of my invention I reserve the right to all such changes in the construction, combination and arrangement of parts as properly fall within the spirit and scope of the invention as claimed.

20 Having thus described my invention, what I claim and desire to secure by Letters Patent, is:

1. In a piston expander, means including a conical member for firmly holding a piston, 25 threaded means upon which said conical member is adjustably mounted, elements operably supported by said conical member and adapted to be inserted within the piston, and mechanism for forcing said elements 30 outwardly to effect expansion of the piston.

2. In a piston expander, means including a conical member for firmly holding a piston, elements having a tongue and groove connection with said conical member and

adapted to be inserted within the piston, 35 spring means for yieldably drawing said elements toward each other, and mechanism for forcing said elements apart to effect expansion of the piston.

3. In a piston expander, a base for supporting a piston to be expanded, a yoke mounted upon said base, a rotary element depending from said yoke, a conical member threaded upon said rotary element for firmly holding the piston upon the base, and piston-expanding mechanism associated with said rotary element and said conical member. 40

4. In a piston expander, a frame, piston-expanding mechanism associated with said frame, and gage means threaded in the opposite sides of said frame for limiting expansion of the piston. 45

5. A piston expander consisting of a base, a yoke supported by said base, a threaded tubular member supported by the yoke, a 50 conical member adjustably mounted upon said threaded member and adapted to hold the piston upon the base, a pair of blocks slidably connected to said conical member and adapted to be inserted within the piston, a wedge member for forcing said blocks in opposite directions to effect expansion of the piston, and a stem journaled in the yoke extending through said tubular member and 55 threaded in said wedge member for actuating the latter.

In testimony whereof I affix my signature.
FRANK A. TRAVIS.
